UNITED STATES PATENT OFFICE.

HARRISON L. WIRT, OF SCHENECTADY, NEW YORK, ASSIGNOR TO GENERAL ELECTRIC COMPANY, A CORPORATION OF NEW YORK.

ELASTIC-FLUID TURBINE.

Application filed August 11, 1924. Serial No. 731,240.

The present invention relates to elastic fluid turbines exhausting to a condenser or other exhaust means and especially to turbines of relatively large capacities operating condensing, that is, exhausting into a condenser.

With the best modern engineering practice it is possible to maintain in a condenser under ordinary operating conditions a vacuum of from 28½" to 29" of mercury which correspond to absolute pressures of 1½" to 1" of mercury, the main limiting feature being the temperature of the cooling water available, and at present there appears to be little likelihood that this can be improved upon so that the possible condenser pressure seems fixed. The thing of importance in connection with a condensing turbine is not the absolute pressure in the condenser, however, but rather the absolute pressure just beyond the last row of buckets and it has been the practice to try to keep this pressure as near to the condenser pressure as possible. Furthermore, it has been recognized that if this pressure could be reduced below that existing in the condenser it would result in an increase in the efficiency of the machine.

However, in the case of large turbines, the volume of exhaust fluid to be handled in enormous and in ordinary practice the pressure on the discharge side of the last row of buckets has been somewhat greater than the condenser pressure, the increase being represented by the drop in pressure required to convey the exhaust fluid from the last row of buckets through the exhaust hood to the condenser. In modern practice this drop in pressure is of the order of 0.05" mercury to 0.15" mercury.

Also, in a turbine, the elastic fluid leaves the last row of buckets with a certain velocity, this velocity being required in order for the elastic fluid to pass the last row of buckets, and the kinetic energy carried away by the elastic fluid stream by virtue of this velocity is termed usually the leaving loss. This kinetic energy is expressed by the formula

$$E = \frac{1}{2}MV^2$$

where E is the kinetic energy, M the mass, and V the velocity. Thus it will be seen that the leaving loss increases with the square of the velocity which means of course, that the velocity of the elastic fluid leaving the last row of buckets should be kept as low

as possible. In order to pass a given quantity of elastic fluid through the last bucket row, the velocity required varies inversely in accordance with the total bucket area so that it is readily seen that by increasing the bucket area, i. e., the length of the buckets and the diameter of the bucket ring, the velocity and hence the leaving losses are decreased. However, the permissible bucket ring diameters and bucket lengths are soon reached due to mechanical considerations so that with large machines the leaving loss may be considerable, the leaving velocity being usually of the order of 700 ft. per second.

Now, it is apparent that if the energy represented by the leaving loss could be usefully employed it would result in a gain in the efficiency of the machine and it has been proposed repeatedly to utilize this energy to decrease the pressure on the discharge side of the last row of buckets by means of passing the exhaust elastic fluid through diffusers or passages which would serve to convert a portion of the velocity into pressure. By this means the kinetic energy of the exhaust fluid would be used to effect the flow of the exhaust fluid to the condenser so that it would be possible to have a pressure on the discharge side of the last row of buckets which is lower than the condenser pressure. However, because of the enormous volumes of elastic fluid and the low pressure drop to be dealt with and the fact that the elastic fluid must be conveyed to a condenser opening, this problem is by no means a simple one, and, so far as I am aware, these proposed arrangements have failed to accomplish their intended purpose. In this connection, it is pointed out that in modern power plant practice, it is necessary to locate the driven machine, such as a generator for example, directly adjacent to the low pressure end of the turbine and in axial alignment with the turbine. This means, of course, that the condenser or condensers must be placed to one side of or below the center line of the turbine set.

The object of my invention is to provide an improved arrangement for accomplishing the above referred to result and for a consideration of what I believe to be novel and my invention, attention is directed to the accompanying description and the claims appended thereto.

In the drawing, Fig. 1 is a top plan view, partly in section, of a turbine structure em-

bodying my invention; Fig. 2 is a side view of the exhaust hood; Fig. 3 is a perspective view of the construction shown in Fig. 1, and Figs. 4 and 5 are transverse, sectional views taken 5 on lines 4-4 and 5-5, respectively, of Fig. 1.

Referring to the drawing, 5 indicates the last row of buckets of an elastic fluid turbine which turbine may be of any suitable type. In the present instance it is shown as being of 10 the impulse type and as comprising a shaft 6 upon which are mounted bucket wheels 7 which rotate in stages formed by nozzle dia- 15 phragms 8. Diaphragms 8 are arranged in the turbine shell 9. The bearing for shaft 6 at the low pressure end of the machine is indicated at 10 and the low pressure packing at 11. Only the low pressure end of the turbine is shown in the drawing. It will be understood that the particular structure indicated 20 is only by way of example and is to be taken as typical of any suitable turbine structure to which my invention may be applied.

I have discovered that I can effect a conversion of velocity of the exhaust fluid into 25 pressure by providing an exhaust housing which comprises first an annular expanding passageway having an admission end of a radial width between walls, i. e., a difference between the inner and outer radii, equal sub- 30 stantially to the length of the buckets of the last bucket row and a length throughout at least the major portion of its circumference equal to at least twice the length of the buck- 35 ets of the last bucket row followed by a plu- rality of branches which change gradually from curved or semi-annular passageways to approximately circular or rectangular pas- 40 sageways before reaching the condenser, such change taking place very gradually with a continual increase in cross-sectional area and 45 without changing substantially the direction of the fluid flow until the greater portion of the diffusion has taken place. To accomplish this result, I have found that for the usual 50 leaving velocities found in present day turbine design, an exhaust passage length equal to at least twice the diameter of the last stage wheel is required and that the area should increase until the final area perpendicular to the elastic fluid flow is of an order two or 55 three times as large as the annular admission area. Preferably, the annular expanding passageway should have a length throughout its 60 entire circumferential area equal to at least twice the last row bucket length. However, 65 for practical reasons, it is difficult sometimes to accomplish this result. For this reason, therefore, I find it necessary in some instances in carrying out my invention, to depart somewhat from this desirable condition. Some de- 70 parture, however, does not affect to an appreciable extent the results obtained.

The admission end of the annular expanding passageway should have a width so as to confine but not obstruct the elastic fluid dis-

charge immediately after it leaves the blades and such passageway should extend in a direction so that while gradually expanding it does not change the direction of flow of the annular fluid stream. Furthermore, the 70 branches into which the annular passageway merges should diverge gradually so as to direct the stream of fluid gradually away from the center line of the turbine at low velocity. In this connection, the diversion of these 75 branches should establish a curvature so gradual that the angle between successive cords drawn parallel to the direction of flow and equal in length to the length of the last row of moving buckets shall not exceed 12°. 80

Referring now to the drawing, 12 indicates the annular expanding passageway of the exhaust hood which, after extending a distance equal to about two bucket lengths throughout at least the major portion of its circumference, divides into two branches 13 and 14 which terminate in openings 15 and 16. Openings 15 and 16 are connected directly to the openings 17 and 18 of suitable condensers indicated at 19 and 20 in Fig. 1.

In order to obtain discharge openings from the branches 13 and 14 of sufficient area for distributing the elastic fluid to the condensers without going to unduly long branches, I preferably cut the branches off at an angle as 95 is best illustrated in Fig. 1, and I then provide stationary buckets or guide blades 21 for turning the elastic fluid and directing it into the condensers. Preferably these blades 21 are shaped so as to provide an expanding cross- 100 section and thereby secure some additional diffusion while turning the elastic fluid. The condenser tubes are indicated at 19a and as will be seen from Fig. 1 of the drawing, by the arrangement illustrated the rows of tubes 105 extend at an angle with the center line of the passageway through which the exhaust fluid flows. By this arrangement it will be seen that the exhaust fluid is fed to the condenser at an angle and the result is obtained that an 110 area of flow to the tubes is obtained which area is greater than the area of the passageway.

With the above described arrangement, I have found that I am enabled to obtain conversion of velocity of the exhaust elastic fluid into pressure without at the same time increasing the overall length of the machine or interfering with the location of the driven machine up close to the low pressure end of the 115 turbine. In order to provide accessibility to the low pressure bearing it is sometimes necessary at the top of the annular portion of the exhaust housing to make it somewhat shorter than two bucket lengths and this is 120 true in the construction illustrated in the drawing. However, having the annular portion somewhat shorter at this point does not affect materially the results obtained.

As stated above, it is the custom, and in fact,

from a practical standpoint, it is necessary to place the machine driven by the turbine, a generator for example, directly adjacent to the low pressure end of the turbine, thus making necessary the positioning of the condenser to one side of or below the turbine and hence in conveying the exhaust elastic fluid from the turbine to the condenser it is necessary to change its direction of flow. In exhaust hoods heretofore proposed for accomplishing conversion of velocity of the exhaust fluid into pressure, it has been attempted to effect such conversion while at the same time changing the direction of flow of the exhaust elastic fluid. By exhaustive tests which I have made, I have demonstrated that the desired result cannot be accomplished in this manner.

As illustrative of the gain to be made by my improved exhaust hood, the following numerical example is given. Assume the case of an average steam turbine of present day design, and operating with a condenser pressure of 1 inch of mercury. In such a turbine with an exhaust hood of usual known construction, the drop in pressure interposed by the exhaust hood is of the order of 0.1 inch of mercury, making the pressure on the discharge side of the last row of blades of the order of 1.1 inches of mercury. With my improved exhaust hood I am enabled under similar operating conditions to maintain a pressure of the order of 0.825 inches of mercury on the discharge side of the last row of blades thus effecting a gain of the order of 0.275 inches of mercury. In large condensing turbines running under the assumed conditions a change of 1 inch mercury in the condenser pressure represents a change of the order of 6% in the water rate. In other words, in such machines the vacuum correction is of the order of 6% per inch of mercury. Under these conditions, therefore, a gain in vacuum of 0.275 inches of mercury on the discharge side of the last blade row would represent a reduction in water rate of about 1.65 per cent.

Or viewed from another aspect, my improved exhaust hood permits of increasing the capacity of a turbine having buckets in its last row of a given length, from 25% to 40% without suffering an increase in the net leaving losses over what they would be with ordinary known types of exhaust hoods. This is because of the fact that the recovery of a part of the residual velocity loss by means of the exhaust hood makes it possible to run with a leaving loss of higher value and still maintain the same economy as before.

Referring now to the structure of the exhaust hood, I preferably form each branch in two sections by dividing them vertically as indicated at 22 thereby providing inner portions 23 and outer portions 24. The inner portions of the two branches are formed integral with each other, being connected by the annular wall 12 and are split horizontally

as is indicated at 25. This enables the inner upper halves of the exhaust housing to be removed for inspection purposes without disturbing the condenser connections.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. The combination with an elastic fluid turbine, of an exhaust hood therefor comprising an annular diverging portion having the difference between the inner and outer radii at its admission end equal to substantially the length of the buckets of the last wheel and a length throughout at least the major portion of its circumference equal to substantially twice the length of such buckets, and a plurality of branches into which said annular portion merges, said branches diverging gradually from the center line of the turbine and acquiring in a distance equal to about two last stage wheel diameters an area equal to at least twice the annular admission area.

2. The combination with an elastic fluid turbine, of an exhaust hood therefor comprising an annular diverging portion having a difference between the inner and outer radii at its admission end equal to substantially the length of the buckets of the last wheel and a length throughout at least the major portion of its circumference equal to substantially twice the length of such buckets, a plurality of branches into which said annular portion merges, said branches curving away and outward from the tips of the buckets of the last stage wheel with a curvature so gradual that the angle between successive cords drawn parallel to the direction of flow and equal in length to the length of the buckets of the last stage wheel shall not exceed 12°.

3. The combination with a horizontal elastic fluid turbine, and two vertical condensers located on opposite sides of the center line of the turbine, of an exhaust hood for conveying exhaust elastic fluid from the turbine to the condensers, said exhaust hood comprising first an annular diverging portion having a length throughout at least the major portion of its circumference equal to approximately twice the length of the buckets of the last stage wheel followed by two branches which gradually increase in area and diverge from the center line of the turbine until they reach the condensers.

4. The combination with a horizontal elastic fluid turbine, and two vertical condensers located on opposite sides of the center line of the turbine and provided with openings which face toward such center line, of an ex-

haust hood for conveying exhaust elastic fluid from the turbine to the condensers, said exhaust hood comprising first an annular portion which increases gradually in area in the direction of flow through it followed by two branches which gradually increase in area to where they join the condenser openings.

5. The combination with a horizontal elastic fluid turbine and two vertical condensers located on opposite sides of the center line of the turbine and provided with openings which face toward such center line, of an exhaust hood for conveying exhaust elastic fluid from the turbine to the condensers, said exhaust hood comprising first an annular portion which increases gradually in area in the direction of flow through it followed by two branches which gradually increase in area to where they join the condenser openings, and 10 turning and diffusion blades set in the plane of discharge of the branches, the entrance edges of such blades facing approximately in the direction of the flow of exhaust elastic fluid and the discharge edges of such blades 15 being normal to the planes of the condenser openings.

6. The combination with a horizontal elastic fluid turbine and vertical condensers on either side of the center line of the turbine, of an exhaust hood therefore comprising an 20 annular diverging portion and plurality of branches which lead to said vertical condensers, said exhaust hood being split horizontally for about half its length at which point it 25 is split vertically.

7. The combination with an elastic fluid turbine, of an exhaust hood therefore comprising a passageway leading to a condenser, the direction of flow in the passageway being 30 different from the direction of flow into the condenser, and a series of blades along the plane of intersection of the two directions of flow, said blades being shaped so as to turn the flow in the new direction and increase 35 the cross-sectional area of flow.

8. The combination with an elastic fluid turbine and a condenser means, of an exhaust hood structure for conveying exhaust elastic fluid from the turbine to the condenser means, said exhaust hood structure comprising first 40 a portion of gradually-increasing area which extends in the direction of flow of exhaust elastic fluid from the turbine for a distance of the order of at least two times the length

of the buckets of the last bucket row and 55 through which the exhaust elastic fluid flows without change in direction, followed by a portion of gradually-increasing area wherein in the direction of flow of the exhaust elastic fluid is changed and directed to the condenser 60 means.

9. The combination with an elastic fluid turbine and a condenser means located to one side of the center line of the turbine, of an exhaust hood for conveying exhaust elastic 65 fluid from the turbine to the condenser means, said exhaust hood comprising first an annular portion of gradually-increasing area which extends in the direction of flow of the exhaust elastic fluid followed by a plurality of branches which diverge gradually 70 and serve to direct the exhaust elastic fluid to the condenser means, and bearing means for the turbine located in the space between 75 said branches and within said annular portion.

10. The combination with a horizontal elastic fluid turbine and two vertical condensers located on opposite sides of the center line of the turbine and provided with openings which face toward said center line, of an exhaust hood for conveying exhaust elastic fluid from the turbine to the condensers, said exhaust hood comprising first an annular portion which increases gradually in area 80 in the direction of flow through it followed by two branches which gradually increase in area to where they join the condenser openings, and bearing means for the turbine located in the space between 85 said branches and within said annular portion.

11. The combination with a horizontal elastic fluid turbine and two condensers located on opposite sides of the center line of the turbine and provided with openings, of an exhaust hood for conveying exhaust elastic fluid from the turbine to the condensers, said exhaust hood comprising first an annular portion which increases gradually in area in the direction of flow through it followed by two branches which gradually increase in area to where they join the condenser openings, and bearing means for the turbine located in the space between 90 said branches and within said annular portion.

In witness whereof, I have hereunto set my hand this 9th day of August, 1924.

HARRISON L. WIRT
